CALENDAR CLOCK

Armando Gasbarro, Jersey City, N.J.

Application September 22, 1952, Serial No. 310,794

10 Claims. (Cl. 58—5)

1

This invention relates to new and useful improvements in calendar clocks.

More particularly, the present invention proposes an improved calendar clock having a standard clock movement either spring wound or electric driven and means to indicate the day of the week and the date, the parts for which can be stamped almost entirely from sheet material for inexpensive fabrication and assembly.

Another object of the present invention proposes forming the calendar clock with a simple calendar mechanism positively driven without cast, forged or cut gears.

Still further, the present invention proposes constructing the calendar clock with a face having day-of-the-week and date openings and rotatable day of the week and date discs behind the openings with springs to bias the discs in proper position for the indicia thereon properly to appear in the openings without marring the discs or impeding their movements.

For further comprehension of the invention and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front view of a calendar clock constructed and arranged in accordance with the present invention with the glass partly broken away.

Fig. 2 is an enlarged view similar to Fig. 1 with parts broken away and some hidden parts shown in dotted outline.

Fig. 3 is a front view of the day-of-the-week disc shown in Figs. 1 and 2.

Fig. 4 is a section taken on line 4—4 of Fig. 3.

Fig. 5 is a section taken on line 5—5 of Fig. 4.

Fig. 6 is a sectional view of the marginal edge portion of the date disc shown in the several figures.

Fig. 7 is an enlarged sectional fragmentary view of the center of the face plate.

Fig. 8 is a sectional view taken on line 8—8 of Fig. 2.

Fig. 9 is a sectional view taken on line 9—9 of Fig. 2.

Fig. 10 is a fragmentary detail view of the backing plate shown in Figs. 7 and 8.

Fig. 11 is a sectional view taken on lines 11—11 of Fig. 10.

Fig. 12 is an enlarged sectional view of a portion of Fig. 10 illustrating the interaction of the discs.

2

Fig. 13 is a fragmentary view of the lower part of the rear side of the face plate.

The calendar clock of the present invention has a casing 15 and a face plate 16 calibrated and numbered in the usual manner with an hour hand 17, a minute hand 18 and a sweep or second hand 19. A glass 20 covers the face plate 16, being held to the casing 15 by a retainer ring 21.

10 Face plate 16 has a central opening 22 (Figs. 7 and 8) a date opening 23 (Fig. 2) and a day-of-the-week opening 24. On the rear side of the face plate 16, a disc 25 is rotatably mounted and centrally disposed.

15 The central disc 25 has a central opening 26 (Fig. 7) to receive a grommet 27, the grommet being frictionally held in the central disc 25 as by a force fit. The grommet 27 also passes through the central opening 22 in the face plate 16 and is rotatable therein. The central opening 26 in the disc 25 and the grommet are polygonal shaped and the grommet is headed over at one end over the front side of the face plate 16 and at the other end over the rear side of the central disc 25 rotatably to secure the disc to the face plate.

20 Central disc 25 has six equally spaced peripheral projections 28 and preferably is formed by stamping from sheet metal although the disc may be molded of plastic or metal if desired.

25 A second or coupling disc 29 is similarly rotatably mounted on the rear side of the face plate 16 adjacent the central or first disc 25. The coupling disc 29 has a single peripheral projection 30 and a centrally concentric circle of twelve lips or abutments 31 equally spaced apart and disposed for engagement by the peripheral projections 28 on the central disc 25. The circular disposed lips or abutments 31 engage with the projections 28 on the disc 25 to rotate the coupling disc 29.

30 A day-of-the-week disc 32 is also rotatably mounted on the rear side of the face plate 16 overlapping the coupling disc 29 and partially overlapping the central disc 25. The day-of-the-week disc 32 is divided into seven equal segments and has seven peripheral projections 33 equally spaced apart. Consecutive day-of-the-week indicia 34 are disposed on the disc 32 between the peripheral projections 33 and disposed for travel

35 beneath the day-of-the-week opening 24 in face plate 16.

Seven downstruck lips or abutments 35 on the disc 32 are radially aligned with the peripheral projections 33 and extend from the day-of-the-week disc disposed for engagement by the single

projection 39 on the second or coupling disc 29 for the disc 29 to move the day-of-the-week disc 32 from one of its abutments 35 to another, each a complete revolution of the coupling disc 29. This movement of the day-of-the-week disc 5 changes the day-of-the-week to the next day, for example, from Monday to Tuesday.

Also held in casing 15 by the retainer ring 21 is a back or backing plate 36. The face plate 16 and the back plate 36 have aligned openings 37 10 and 38 (Fig. 8), respectively, adjacent the date opening 23 in the face plate. Back plate 36 has upstruck peripheral spacer or spacing ears 39 (Fig. 11) and the face plate 16 has spacing ear receiving peripheral openings 39' in order for the back 15 plate to hold the face plate spaced from it. A stud 40 extending through the aligned openings 37 and 38 provides means to hold the face plate against the back plate ears 39 as does the retainer ring 21. A spring 41 on the front of the 20 face plate 16 below the stud 40 biases the stud upwardly.

Secured to the back plate 36 is a clock movement 42 electrically driven but which can be spring wound if desired. Any standard movement can be used. Back plate 36 also has a central opening 43 (Fig. 8) through which the central shaft 44 of the clock movement 42 passes for free rotation. The back plate 36 and the front plate 16 do not rotate.

A date disc 45 having a central shaft opening 46 is freely rotatable on the shaft 44 between the back plate 36 and the face plate 16 and behind the discs 25, 29 and 32.

The date disc 45 has thirty-one upstanding 35 abutments or upstruck lips 47 (Fig. 2) on its marginal edge portion positioned for engagement with and by the seven peripheral projections 33 on the day-of-the-week disc 32. The date disc 45 also has date indicia 48, from "one" to "thirty-one," consecutively disposed between the marginal edge portion abutments 47 and underlying, in its path of travel, the date opening 23 in the face plate.

Leaf spring 49 (Figs. 10 and 11) is secured as by welding or soldering to the front of the back plate 36 and provides resilient means to bias the date disc 45 toward the face plate 16 adjacent the date opening 23 in the face plate to insure engagement of the date disc abutments 47 with the day-of-the-week peripheral projections 33 at this point.

A similar leaf spring 50 (Fig. 13) is secured to the rear side of the face plate 16 providing resilient means to bias the day-of-the-week disc 32 back from the opening 24 to prevent scraping of the indicia 34 of the day-of-the-week disc 32 on the edges of this face plate opening.

The central shaft 44 of the clock movement 42 has an hour hand driving polygonal-shaped portion 51 to conform to the similar shaped central opening 26 in the central or first disc 25 and to central disc 25.

Rotation of the central shaft's hour hand driving portion 51 as the hour hand 17 is moved by the clock movement 42 rotates the central disc 25 each hour through an arc of thirty degrees. Thus each two hours one of the six projections 28 on the central disc 25 moves the coupling disc from one of its abutments 31 to the next. It is thus apparent that in two complete revolutions of the central disc 25, taking twenty-four hours, the twelve-abutment coupling disc 29 will move through one complete revolution.

This one revolution is sufficient for the single 75

projection 30 on the coupling disc 29 to complete one cycle of travel and move the day-of-the-week disc from one abutment 35 to the next, thus changing the day of the week appearing in the day-of-the-week opening 24 of the face disc 16. At the same time, one of the peripheral projections 33 on the day-of-the-week disc 32 engages one of the abutments 47 on the date disc 45 rotating the date disc through $\frac{1}{41}$ of its circumference. This changes the date to the next higher numeral at the same time as the day is changed to the next day in the week.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a calendar clock, a face plate having a central shaft opening and date and day-of-the-week openings, a disc rotatably mounted and centrally disposed on the rear side of the face plate, said disc having a polygonal central opening and six peripheral projections equally spaced apart, a second disc rotatably mounted on the rear side of the face plate adjacent the first disc, said second disc having a single peripheral projection and a centrally concentric circle of twelve abutments equally spaced and disposed for engagement with the projections on the first disc to rotate the second disc, a day-of-the-week disc rotatably mounted on the rear side of the face plate and having seven peripheral projections equally spaced apart and seven abutments radially aligned with the projections and extending from the day-of-the-week disc for engagement by the single projection on the second disc for said second disc to move the day-of-the-week disc, said day-of-the-week disc having day-of-the-week indicia consecutively disposed on the disc between the peripheral projections and disposed for travel behind the day-of-the-week opening in the face plate, a date disc having a central shaft opening, a central shaft extending through the date disc and the face plate, said shaft having a polygonal-shaped hour hand receiving section extending through the like shaped central opening of the first disc to rotate that disc, said date disc being freely rotatable on the shaft behind the face plate and having thirty-one upstanding abutments on its marginal edge portion positioned for engagement with the seven peripheral projections on the day-of-the-month disc, said date disc having date indicia on the peripheral edge portion consecutively disposed between the marginal edge portion abutments and behind the date opening in the face plate.

2. In a calendar clock, a face plate having a central shaft opening and date and day-of-the-week openings, a disc rotatably mounted and centrally disposed on the rear side of the face plate, said disc having a polygonal central opening and six peripheral projections equally spaced apart, a second disc rotatably mounted on the rear side of the face plate adjacent the first disc, said second disc having a single peripheral projection and a centrally concentric circle of twelve abutments equally spaced and disposed for engagement with the projections on the first disc to rotate the second disc, a day-of-the-week disc

rotatably mounted on the rear side of the face plate and having seven peripheral projections equally spaced apart and seven abutments radially aligned with the projections and extending from the day-of-the-week disc for engagement by the single projection on the second disc for said second disc to move the day-of-the-week disc, said day-of-the-week disc having day-of-the-week indicia consecutively disposed on the disc between the peripheral projections and disposed for travel behind the day-of-the-week opening in the face plate, a date disc having a central shaft opening, a central shaft extending through the date disc and the face plate, said shaft having a polygonal-shaped hour hand receiving section extending through the like shaped central opening of the first disc to rotate that disc, said date disc being freely rotatable on the shaft behind the face plate and having thirty-one upstanding abutments on its marginal edge portion positioned for engagement with the seven peripheral projections on the day-of-the-month disc, said date disc having date indicia on the peripheral edge portion consecutively disposed between the marginal edge portion abutments and behind the date opening in the face plate, a back plate with a central shaft opening behind the date disc, said face plate having spacing ear receiving peripheral openings and spacing ears on the back plate to hold the face plate spaced from the back plate.

3. In a calendar clock, a face plate having a central shaft opening and date and day-of-the-week openings, a disc rotatably mounted and centrally disposed on the rear side of the face plate, said disc having a polygonal central opening and six peripheral projections equally spaced apart, a second disc rotatably mounted on the rear side of the face plate adjacent the first disc, said second disc having a single peripheral projection and a centrally concentric circle of twelve abutments equally spaced and disposed for engagement with the projections on the first disc to rotate the second disc, a day-of-the-week disc rotatably mounted on the rear side of the face plate and having seven peripheral projections equally spaced apart and seven abutments radially aligned with the projections and extending from the day-of-the-week disc for engagement by the single projection on the second disc for said second disc to move the day-of-the-week disc, said day-of-the-week disc having day-of-the-week indicia consecutively disposed on the disc between the peripheral projections and disposed for travel behind the day-of-the-week opening in the face plate, a date disc having a central shaft opening, a central shaft extending through the date disc and the face plate, said shaft having a polygonal-shaped hour hand receiving section extending through the like shaped central opening of the first disc to rotate that disc, said date disc being freely rotatable on the shaft behind the face plate and having thirty one upstanding abutments on its marginal edge portion positioned for engagement with the seven peripheral projections on the day-of-the-month disc, said date disc having date indicia on the peripheral edge portion consecutively disposed between the marginal edge portion abutments and behind the date opening in the face plate, a back plate with a central shaft opening behind the date disc, said face plate having spacing ear receiving peripheral openings and spacing ears on the back plate to hold the face plate spaced from the back plate.

back plate, and means to hold the face plate against the back plate ears.

4. In a calendar clock, a face plate having a central shaft opening and date and day-of-the-week openings, a disc rotatably mounted and centrally disposed on the rear side of the face plate, said disc having a polygonal central opening and six peripheral projections equally spaced apart, a second disc rotatably mounted on the rear side of the face plate adjacent the first disc, said second disc having a single peripheral projection and a centrally concentric circle of twelve abutments equally spaced and disposed for engagement with the projections on the first disc to rotate the second disc, a day-of-the-week disc rotatably mounted on the rear side of the face plate and having seven peripheral projections equally spaced apart and seven abutments radially aligned with the projections and extending from the day-of-the-week disc for engagement by the single projection on the second disc for said second disc to move the day-of-the-week disc, said day-of-the-week disc having day-of-the-week indicia consecutively disposed on the disc between the peripheral projections and disposed for travel behind the day-of-the-week opening in the face plate, a date disc having a central shaft opening, a central shaft extending through the date disc and the face plate, said shaft having a polygonal-shaped hour hand receiving section extending through the like shaped central opening of the first disc to rotate that disc, said date disc being freely rotatable on the shaft behind the face plate and having thirty one upstanding abutments on its marginal edge portion positioned for engagement with the seven peripheral projections on the day-of-the-month disc, said date disc having date indicia on the peripheral edge portion consecutively disposed between the marginal edge portion abutments and behind the date opening in the face plate, a back plate with a central shaft opening behind the date disc, said face plate having spacing ear receiving peripheral openings and spacing ears on the back plate to hold the face plate spaced from the back plate, and means to hold the face plate against the back plate ears, and resilient means on the rear side of the face plate adjacent the day-of-the-week opening to bias the day-of-the-week disc back from the opening to prevent scraping of the indicia of said disc on the edges of said opening.

5. In a calendar clock, a face plate having a central shaft opening and date and day-of-the-week openings, a disc rotatably mounted and centrally disposed on the rear side of the face plate, said disc having a polygonal central opening and six peripheral projections equally spaced apart, a second disc rotatably mounted on the rear side of the face plate adjacent the first disc, said second disc having a single peripheral projection and a centrally concentric circle of twelve abutments equally spaced and disposed for engagement with the projections on the first disc to rotate the second disc, a day-of-the-week disc rotatably mounted on the rear side of the face plate and having seven peripheral projections equally spaced apart and seven abutments radially aligned with the projections and extending from the day-of-the-week disc for engagement by the single projection on the second disc for said second disc to move the day-of-the-week disc, said day-of-the-week disc having day-of-the-week indicia consecutively disposed on the disc between the peripheral projections and disposed for travel behind the day-of-the-week opening in the face plate.

in the face plate, a date disc having a central shaft opening, a central shaft extending through the date disc and the face plate, said shaft having a polygonal-shaped hour hand receiving section extending through the like shaped central opening of the first disc to rotate that disc, said date disc being freely rotatable on the shaft behind the face plate and having thirty one upstanding abutments on its marginal edge portion positioned for engagement with the seven peripheral projections on the day-of-the-month disc, said date disc having date indicia on the peripheral edge portion consecutively disposed between the marginal edge portion abutments and behind the date opening in the face plate, a back plate with a central shaft opening behind the date disc, said face plate having spacing ear receiving peripheral openings and spacing ears on the back plate to hold the face plate spaced from the back plate, and means to hold the face plate against the back plate ears, and resilient means on the rear side of the face plate adjacent the day-of-the-week opening to bias the day-of-the-week disc back from the opening to prevent scraping of the indicia of said disc on the edges of said opening, and resilient means on the back plate to bias the date disc toward the face plate adjacent the date opening in the face plate to insure engagement of the date disc abutments with the day-of-the-week peripheral projections at this point.

6. In a calendar clock, a face plate having a central shaft opening and date and day-of-the-week openings, a disc rotatably mounted and centrally disposed on the rear side of the face plate, said disc having a polygonal central opening and six peripheral projections equally spaced apart, a second disc rotatably mounted on the rear side of the face plate adjacent the first disc, said second disc having a single peripheral projection and a centrally concentric circle of twelve abutments equally spaced and disposed for engagement with the projections on the first disc to rotate the second disc, a day-of-the-week disc rotatably mounted on the rear side of the face plate and having seven peripheral projections equally spaced apart and seven abutments radially aligned with the projections and extending from the day-of-the-week disc for engagement by the single projection on the second disc for said second disc to move the day-of-the-week disc, said day-of-the-week disc having day-of-the-week indicia consecutively disposed on the disc between the peripheral projections and disposed for travel behind the day-of-the-week opening in the face plate, a date disc having a central shaft opening, a central shaft extending through the date disc and the face plate, said shaft having a polygonal-shaped hour hand receiving section extending through the like shaped central opening of the first disc to rotate that disc, said date disc being freely rotatable on the shaft behind the face plate and having thirty one upstanding abutments on its marginal edge portion positioned for engagement with the seven peripheral projections on the day-of-the-month disc, said date disc having date indicia on the peripheral edge portion consecutively disposed between the marginal edge portion abutments and behind the date opening in the face plate, a back plate with a central shaft opening behind the date disc, said face plate having spacing ear receiving peripheral openings and spacing ears on the back plate to hold the face plate spaced from the back plate, said face plate and back plate having aligned openings adjacent the date opening in the face plate and a stud extending through said aligned openings to hold the face plate against the back plate ears, and a spring on the front of the face below the stud biasing the stud upwardly.

7. In a calendar clock, a face plate having a central shaft opening and date and day-of-the-week openings, a disc rotatably mounted and centrally disposed on the rear side of the face plate, said disc having a polygonal central opening and six peripheral projections equally spaced apart, a second disc rotatably mounted on the rear side of the face plate adjacent the first disc, said second disc having a single peripheral projection and a centrally concentric circle of twelve abutments equally spaced and disposed for engagement with the projections on the first disc to rotate the second disc, a day-of-the-week disc rotatably mounted on the rear side of the face plate and having seven peripheral projections equally spaced apart and seven abutments radially aligned with the projections and extending from the day-of-the-week disc for engagement by the single projection on the second disc for said second disc to move the day-of-the-week disc, said day-of-the-week disc having day-of-the-week indicia consecutively disposed on the disc between the peripheral projections and disposed for travel behind the day-of-the-week opening in the face plate, a date disc having a central shaft opening, a central shaft extending through the date disc and the face plate, said shaft having a polygonal-shaped hour hand receiving section extending through the like shaped central opening of the first disc to rotate that disc, said date disc being freely rotatable on the shaft behind the face plate and having thirty one upstanding abutments on its marginal edge portion positioned for engagement with the seven peripheral projections on the day-of-the-month disc, said date disc having date indicia on the peripheral edge portion consecutively disposed between the marginal edge portion abutments and behind the date opening in the face plate, a back plate with a central shaft opening behind the date disc, said face plate having spacing ear receiving peripheral openings and spacing ears on the back plate to hold the face plate spaced from the back plate, said face plate and back plate having aligned openings adjacent the date opening in the face plate and a stud extending through said aligned openings to hold the face plate against the back plate ears, and a spring on the front of the face below the stud biasing the stud upwardly.

8. In a calendar clock, a face plate having a central shaft opening and date and day-of-the-week openings, a disc rotatably mounted and centrally disposed on the rear side of the face plate, said disc having a polygonal central opening and six peripheral projections equally spaced apart, a second disc rotatably mounted on the rear side of the face plate adjacent the first disc, said second disc having a single peripheral projection and a centrally concentric circle of twelve abutments equally spaced and disposed for engagement with the projections on the first disc to rotate the second disc, a day-of-the-week disc rotatably mounted on the rear side of the face plate and having seven peripheral projections equally spaced apart and seven abutments radially aligned with the projections and extending from the day-of-the-week disc for engagement by the single projection on the second disc for said second disc to move the day-of-the-week disc, said day-of-the-week disc having day-of-the-week indicia consecutively disposed on the disc between the peripheral projections and disposed for travel behind the day-of-the-week opening in the face plate, a date disc having a central shaft opening, a central shaft extending through the date disc and the face plate, said shaft having a polygonal-shaped hour hand receiving section extending through the like shaped central opening of the first disc to rotate that disc, said date disc being freely rotatable on the shaft behind the face plate and having thirty one upstanding abutments on its marginal edge portion positioned for engagement with the seven peripheral projections on the day-of-the-month disc, said date disc having date indicia on the peripheral edge portion consecutively disposed between the marginal edge portion abutments and behind the date opening in the face plate, a back plate with a central shaft opening behind the date disc, said face plate having spacing ear receiving peripheral openings and spacing ears on the back plate to hold the face plate spaced from the back plate, said face plate and back plate having aligned openings adjacent the date opening in the face plate and a stud extending through said aligned openings to hold the face plate against the back plate ears, and a spring on the front of the face below the stud biasing the stud upwardly.

the-week indicia consecutively disposed on the disc between the peripheral projections and disposed for travel behind the day-of-the-week opening in the face plate, a date disc having a central shaft opening, a central shaft extending through the date disc and the face plate, said shaft having a polygonal-shaped hour hand receiving section extending through the like shaped central opening of the first disc to rotate that disc, said date disc being freely rotatable on the shaft behind the face plate and having thirty one upstanding abutments on its marginal edge portion positioned for engagement with the seven peripheral projections on the day-of-the-month disc, said date disc having date indicia on the peripheral edge portion consecutively disposed between the marginal edge portion abutments and behind the date opening in the face plate, a back plate with a central shaft opening behind the date disc, said face plate having spacing ear receiving peripheral openings and spacing ears on the back plate to hold the face plate spaced from the back plate, said abutments on the second disc and on the day-of-the-week disc and on the date disc being lips struck from the material itself of the second disc and day-of-the-week disc and date disc respectively.

9. In a calendar clock, a face plate having a central shaft opening and date and day-of-the-week openings, a disc rotatably mounted and centrally disposed on the rear side of the face plate, said disc having a polygonal central opening and six peripheral projections equally spaced apart, a second disc rotatably mounted on the rear side of the face plate adjacent the first disc, said second disc having a single peripheral projection and a centrally concentric circle of twelve abutments equally spaced and disposed for engagement with the projections on the first disc to rotate the second disc, a day-of-the-week disc rotatably mounted on the rear side of the face plate and having seven peripheral projections equally spaced apart and seven abutments radially aligned with the projections and extending from the day-of-the-week disc for engagement by the single projection on the second disc for said second disc to move the day-of-the-week disc, said day-of-the-week disc having day-of-the-week indicia consecutively disposed on the disc between the peripheral projections and disposed for travel behind the day-of-the-week opening in the face plate, a date disc having a central shaft opening, a central shaft extending through the date disc and the face plate, said shaft having a polygonal-shaped hour hand receiving section extending through the like shaped central opening of the first disc to rotate that disc, said date disc being freely rotatably on the shaft behind the face plate and having thirty one upstanding abutments on its marginal edge portion positioned for engagement with the

5 seven peripheral projections on the day-of-the-month disc, said date disc having the date indicia on the peripheral edge portion consecutively disposed between the marginal edge portion abutments and behind the date opening in the face plate, a back plate with a central shaft opening behind the date disc, said face plate having spacing ear receiving peripheral openings and spacing ears on the back plate to hold the face plate spaced from the back plate, said abutments on the second disc and on the day-of-the-week disc and on the date disc being lips struck from the material itself of the second disc and day-of-the-week disc and date disc respectively.

10 15. A calendar clock comprising a casing, a back plate and means to hold the back plate in the casing, a movement secured to the rear side of the back plate with a central shaft rotatably extending through the center of the back plate, upstruck peripheral spacer ears on the back plate, a face plate having a central opening to receive the shaft and spacer ear openings to receive the ears of the back plate and hold the two plates in spaced relation, said face plate having date 20 openings and day-of-the-week openings, a date disc rotatably mounted on the central shaft adjacent the back plate between the back plate and the face plate, said date disc having thirty one upstruck lips equally spaced apart on its marginal edge portion and consecutive date indicia between the lips exterior thereof disposed behind the date opening in the face plate, said central shaft having an hour hand driving polygonal-shaped portion, a central disc rotatably 25 secured to the rear side of the face plate and having a polygonal shaped central opening to receive said polygonal portion of the shaft, said central disc having six equally spaced peripheral projections, a day-of-the-week disc rotatably 30 mounted on the rear side of the face plate spaced from the central disc, said day-of-the-week disc having seven peripheral projections and consecutive day-of-the-week indicia between the 35 projections disposed for travel behind the day-of-the-week opening in the face plate, seven equally spaced downstruck lips radially aligned with the projections on the day-of-the-week disc and a coupling disc rotatably mounted on the rear side of the face plate with twelve lips circularly disposed for engagement by the projections on the central disc and a single projection disposed to engage seriatim the seven downstruck lips for step movement of the day-of-the-week disc.
